UNITED STATES PATENT OFFICE

JOSEPH CAMIRÉ, OF CENTRAL FALLS, RHODE ISLAND

HOT AIR FURNACE

Application filed September 12, 1929. Serial No. 392,161.

This invention relates to improvements in hot air furnaces of the type employed for heating buildings and dwellings.

The primary object of this invention is to provide a device of the above mentioned character which is adapted to utilize the burnt gases of the combustion chamber to the most possible extent.

A further object of this invention is to provide a hot air furnace composed of sectional units which may readily be dissembled for facilitating easy shipping and handling.

A still further object of this invention is to provide a structure of the above mentioned character having a heat radiating chamber associated with the fire chamber whereby a flue is formed within the outer casing for causing the flue gases to travel the double length of the radiating chamber.

A still further object of this invention is to provide a device of the above mentioned character adapted to be easily and cheaply constructed and simple and efficient in operation.

Other objects and advantages of this invention will become apparent during the course of the following description, forming a part of this specification and in which,

Figure 1 is a top plan view of the invention partly in section, showing the simple arrangement of the casing and the fire box chamber;

Figure 2 is a side elevational view of the invention partly in section showing the flue chamber mounted within the hot air casing and upon the fire box chamber;

Figure 3 is a front elevational view of the invention showing the novel arrangement of the fire door and the removable closure for gaining access to the flue chamber;

Figure 4 is a vertical cross-sectional view of the invention showing the general construction of the parts in their assembled position; and

Figure 5 is a horizontal cross-sectional view of the same, showing more clearly the general position of flue chamber relative to the hot air casing.

For the purpose of more clearly describing the invention, reference is made to the draw-

ings, wherein the reference character 5 designates a metallic casing having side walls 6 connected by opposite end walls 7. The side and end walls 6 and 7 are provided with a bottom 8 and a removable cover 9 having a downwardly depending flange 10 on its edges adapted to overlie the upper edges of the sides and end walls 6 and 7 respectively, in order to form an air tight connection.

Elongated openings 11 are provided in the side walls 6, of the hot air casing 5 and are furnished with air intake elbows 12 having upwardly extending mouths 13, presenting a horizontal opening 14 to the atmosphere, either interiorly or exteriorly of the building.

Rigidly secured to the cover 9 are hot air pipe connections 15 which communicate with openings 16 to the interior of the hot air casing 5 and are adapted for the attachment of flue pipes leading to the room or rooms to be heated.

One of the end walls 6 has an opening 17 at the lower portion thereof while an opening 18 is formed at the uppermost portion of the end wall 7 adapted to be closed by a closure plate 19, having an inwardly extending rectangular flange 20, engaging the edges of the opening 18. Suitable handles 21 are secured to the cover plate 19 for facilitating the removal thereof.

A fire box 22 is placed in the casing 5 and constitutes a box like structure having a bottom 23 and a top 24 spaced by side and end walls 25 and 26 respectively, whereby a combustion chamber is formed above the grate bars 27, and an ash pit therebelow. Supporting legs 28 are secured to the bottom 23 of this fire box 22 for spacing the same from the bottom 8 of the casing 5. One of the end walls 26 of the fire box 22 is placed in juxtaposition to the opening 17, in the end wall 7 of the casing 5 and is provided with a hinged door 29, hinged to the fire box as at 30. The door 29 is also formed with openings 31 closed by a sliding plate 32 operated in the usual manner and a handle 33 is provided for opening and closing the door 29. The door 29 communicates with the fire chamber of the fire box 22, and is intended for

coaling the same, while the ashes are removed through a trough 35, secured to the end wall 7 at the bottom thereof and the trough 35 is open at the top adapted to be closed by 5 a horizontally swinging cover plate 36, hinged to one edge of a shelf 37 as at 38. The trough 35 communicates with the interior of the fire box in alignment with the ash pit thereof whereby easy removal of the 10 ashes may be had.

A flue chamber 39 is mounted on the fire box top 24, and as shown in the drawings comprises an elongated rectangular box having a centrally located baffle plate 40 having 15 an opening 41 at the front end thereof, whereby the flue gases from the fire box 22 may pass through a neck 42 into one end of the flue chamber 39 and around the baffle plate 40 by way of the opening 41 whereby the gases are 20 allowed to pass through a flue pipe 43, secured to the top wall of the flue chamber 39 at the remotest point from the opening 41.

Closures 46 are provided for clean out openings 47 in the front wall 48 of the flue 25 chamber and these closures may be removed through the opening 18 in the front wall of the casing 5. It will be noted that the flue pipe 43 passes through an opening in the cover 9 and forms an airtight connection 30 therewith to prevent the escape of hot air from the casing 5. The flue chamber 39 is further supported from the top of the fire box 24, by spacing members 50.

It is to be understood that various changes 35 in the shape, size and arrangement of parts may be resorted to without departing from the spirit of the invention or the scope of the subjoined claim.

I claim:

40 A hot air heater of the character described, comprising a sheet metal hot air casing constituting a portable unit having air inlets at the bottom thereof, and air outlets at the uppermost portion thereof, a fire box removably mounted in the hot air casing, means 45 for feeding air to the fire box, including an opening in one wall thereof communicating with an opening in the hot air casing, a flue chamber mounted on the fire box, comprising 50 an elongated box-like structure having an internal baffle plate extending centrally in respect thereto, and means for allowing the gases of the fire box to pass through the flue chamber to the exterior of the hot air 55 casing.

In testimony whereof I affix my signature.
JOSEPH CAMIRE.
